HEEL COVERING MACHINE

Frank A. O'Donnell, Naugatuck, Conn., assignor
to United States Rubber Company, New York,
N. Y., a corporation of New Jersey

Application January 13, 1951, Serial No. 205,925

4 Claims. (Cl. 12—49.1)

1

This invention relates to a heel covering machine for pressing the tacky surface of the flexible heel cover onto a heel foundation. The invention relates particularly to the combination of pairs of horizontal and vertical pressure rolls for pressing the cover onto the heel foundation and a pair of spaced plates located between the pairs of rolls for folding the top and bottom edges of the heel cover over the top and bottom marginal edges of the heel foundation before the 10 edges are pressed by the horizontal rolls.

Machines have been made heretofore for applying the heel cover to the sides of the heel foundation, but further manual labor was required to fold the top and bottom edges of the heel cover over the top and bottom marginal surfaces of the heel foundation. The edge folding operation was performed manually in its entirety, or was performed as an independent operation partly by hand and with the assistance 15 of a power driven apparatus.

In accordance with the present invention the entire operation of pressing the heel cover to the heel foundation is performed by the machine described herein as a continuous, integrated 20 operation with a single handling of the heel cover and foundation. A great saving of labor and time is thus made by the use of the machine.

This invention, its objects and advantages will be further described in reference to the accompanying drawings, in which:

Fig. 1 is a front elevation of the heel covering machine embodying this invention, in which parts are shown in section;

Fig. 2 is an enlarged top and side isometric 35 view of the assembled heel cover and heel foundation, which has been prepared to be placed in and processed by the machine;

Fig. 3 is a top and side isometric view of a 40 covered heel which has been processed by the machine;

Fig. 4 is an enlarged side elevational view of the left side of the machine as viewed in reference to Fig. 1, and showing the assembled heel cover and foundation in the process of passing 45 through the machine; and

Fig. 5 is a top plan view of the machine in the process of applying the heel cover to the heel foundation as shown in Fig. 4.

Referring to Fig. 1 of the drawings, the heel covering machine embodying this invention comprises a pair of horizontal rolls 10 and 11, which are positioned behind a pair of vertical rolls 12, and a pair of horizontally arranged heel cover edge folding plates 13 and 14 positioned

2

between the pair of horizontal rolls 10 and 11 and the pair of vertical rolls 12. The cylindrical surfaces of the pairs of horizontal rolls 10 and 11 and of the vertical rolls 12 are made of resilient yieldable material, such as rubber, and such surfaces are adapted to press the adhesively coated surface 15 of the heel cover 16 onto the heel foundation 17, which has been prepared as an assembly 18, as shown in Fig. 2. A pair of rollers 19 are located between the vertical rolls 12 for supporting the heel foundation 17 as it and the cover 16 thereon passes between the rolls. The heel assembly 18 passes through the machine from the front to the rear and the cover 16 is first pressed to the back 20 and sides 21 of the heel foundation 17 by the vertical rolls 12. The top and bottom edges 22 of the cover 16 are folded over the top and bottom surfaces of the foundation 17, and such folded over edges are 20 pressed down by the horizontal rolls 10 and 11.

In the preparation of the assembly of the heel cover 16 and the foundation 17, as shown in Fig. 2, the foundation 17 is preferably coated with latex and dried. One surface 15 of the cover 16 is coated with a suitable adhesive, such as latex, and the center of the cover is applied to the back 20 of the heel foundation. The heel cover 16 is bent around the sides 21 of the heel foundation 17 until the ends 23 extend over the forward end 24 of the foundation 17.

As shown in Fig. 2, the upwardly facing surface of the heel foundation 17 is the outside tread surface, or the surface to which the tread member is attached. Such surface is divided into a flat portion 25 forming the heel proper, and a tapered curved section 26, which forms the shank portion of the wedge shaped heel. The two sections are separated by the breast 27 of the heel.

In processing the heel assembly 18, the operator grasps the forward end 24, and pushes its rear end 20 against one of the vertical pressing rolls 12 and then between the rolls while the surface of the heel foundation opposite the heel tread surface 24 is supported on the supporting rollers 19. The rolls 12 are preferably made of sponge rubber, and their adjacent peripheries being spaced apart less than the width of the heel foundation, the cylindrical surfaces are forced inwardly and presses the sides of the heel cover 16 against the sides 21 of the heel foundation, and also bends the top and bottom edges 22 of the cover over the top and bottom surfaces of the heel foundation 17. As the operator continues to force the heel assembly 18 between the 55 vertical rolls 12, the rear end 20 of the assembly

passes between the cover edge folding plates 13 and 14, and the cover edges 22 are folded over and in contact with the top and bottom surfaces of the heel foundation 17. When the rear end 20 of the heel assembly engages the peripheries of the horizontal rolls 10 and 11, the machine is set in motion by the operator and the bottom roll 14 is driven by the motor 28 through a one revolution clutch 29 in the direction indicated by the arrow A. The heel assembly 18 is forced between the horizontal rolls 10 and 11 by the forward motion of the vertical rolls 12. The pressure exerted by the horizontal rolls 10 and 11 on the folded over edges 22 of the heel cover presses the edges down firmly against the adhesively coated heel foundation as the assembly is drawn between the rolls by the driven roll 11. The heel 18' is discharged from the back end of the machine in its finished condition as shown in Fig. 3, in which the sides and the top and bottom edges 22 of the heel cover 16 have been tightly pressed against the heel foundation 17 and adhered thereto. Preferably, the surface of the horizontal rolls 10 and 11 are considerably less yieldable than the surface of the vertical rolls 12. The horizontal rolls are preferably made of an outer shell 30 of soft, solid elastic rubber, which is backed by an inner core 31 of softer solid rubber, as shown in Figs. 1 and 4.

The horizontal upper roll 10 is bounded to a shaft 32 which is rotatably mounted in blocks 33 (Fig. 4) at each end of the shaft. Each block 33 is slidable vertically in the frame 34, and the upper roll 10 is resiliently pressed towards the lower roll 11 by springs 35, which are compressed between the blocks 33 and the ends of screws 36 threaded into bores 36' in the frame 34. The bores 36' provide sockets for the springs, and the screws 36 may be turned to adjust the tension on the springs 35.

It will be noted that the rear end 20 of the heel foundation 17 is thicker than the forward end 24, and that the thick rear end 20 enters between the horizontal rolls in advance of the thinner end. It is therefore necessary to separate the rolls 10 and 11 a sufficient distance to permit the entry of the thick end 20 of the heel foundation into the nip between the rolls, and thereafter permit the roll 10 to approach the roll 11 so that the thinner shank portion 26 of the wedge shaped heel will be pressed as it is drawn between the rolls. For such purpose the spacing of the rolls 10 and 11 is controlled by two like cams 37, one of which is keyed to each end of the shaft 38 of the lower roll 11. The cams 37 are provided with outer peripheral cam surfaces 39 which operate on rollers 40, one of which is keyed to each end of the shaft 32 of the upper roll 10. As shown in Fig. 4, the cams 37 are driven in the direction of the arrow A. The rollers 40 are on the high points 41 of the cam surfaces 39, and the roller 10 has been raised to its highest point for the admission of the thick end 20 of the heel foundation 17 into the nip between the horizontal rolls. When the high points 41 on the surfaces of the cams 39 are in contact with the rolls 40, the space between the rolls 10 and 11 is slightly less than the thickness of the thickest portion of the heel foundation 17, but the space is sufficient to permit the entry of the rear end 20 of the heel foundation when it is pushed by the forward movement of the vertical rolls 12. As the flat thick portion of the heel foundation passes between the horizontal rolls, the roll 10 is moved upwardly, and the full pressure of the

springs 35 are transmitted through the roll 10 to the folded over top and bottom edges 22 of the heel cover 16. Before the breast 27 of the heel foundation 17 passes between the nip of the rolls 10 and 11, the abruptly depressed portions 42 of the cam surfaces 39 pass underneath the rollers 40, and the full pressure of the springs 35 is permitted to be exerted on the curved tapered portion 26 of the heel foundation extending beyond the breast 27. After the forward end 24 of the heel foundation passes between the nip of the rolls 10 and 11, the upper roll 10 is supported against the downward pressure of the compression springs 35 by the lower portions 43 of the cam surfaces 39 which resume contact with the rollers 40. The cam surfaces 39 continue to rotate in the direction of the arrow A until their high points 41 again arrive under the rollers 40 and raise the horizontal roll to its highest point, as shown in Fig. 4. At this point the one revolution clutch 29 disengages the driven shaft 38 of the lower roll 11 from the motor 28.

The cam 37 is also provided with the side cam surfaces 44 for controlling the movement of the vertical rolls 12 towards each other, and also towards and away from the horizontal rolls 10 and 11. For that purpose the vertical rolls 12 are mounted on vertical shafts 45, which are rotatably mounted in like yokes 46, one of which is mounted on each side of the machine. As shown in Fig. 5, each yoke 46 is formed on one branch 47 of an L-shaped arm 48 having its other branch 49 pivotally mounted on a vertically extending stud screw 50, which is threaded into the frame 34 of the machine. A roller 51 is rotatably mounted on the branch 49 of the arm 48, and such roller is spring pressed against the side cam surface 44 by a leaf spring 52, having one end secured to the frame 34 by a screw 53, and having its other end bearing against the branch 49 of the arm 48 so as to hold it in contact with the cam surface 44.

As shown in Figs. 4 and 5, the rollers 51 are at the low point of the side cam surfaces 44, and they will immediately ride up the inclines 54 leading to the high portions 55 of the cam surfaces 44 as the cams 37 begin to rotate in the direction of the arrow A. As the rollers 51 ride upon the high portions 55 of the side cam surfaces, they are forced axially outwardly, and the branches 49 of the arms 48 are pivoted about the screws 50. The pivotal movements of the arms 48 force the vertical rollers 12 towards each other and also towards the nip of the rolls 10 and 11. It will be noted that the foregoing movements of the rolls 12 occur immediately after the breast 27 of the heel foundation 17 has passed between the nip of the rolls 12. Two advantageous results are thereby accomplished. First, the approach of the rolls 12 in closer proximity at this point effectively folds the top and bottom edges 22 of the heel cover 16 over the top and bottom surfaces of the tapered thinner portion of the heel foundation 17, which is not contacted by the folding plates 13 and 14. Second, the movement of the vertical rolls 12 are rotated towards the nip of the rolls 10 and 11 and force the assembled heel assembly 18 between the nip of the horizontal rolls and thereby causes the assembly to be drawn by the driven roll 11 into and through the nip.

The upper and lower cover edge folding plates 13 and 14 have forwardly extending concavely curved edges 55' as shown in Fig. 5, so that they will more effectively fold the edges 22 of the heel cover over the top and bottom surfaces of the

5

heel foundation 17. The plates 13 and 14 are also adjustable vertically. The lower plate 14 is secured to two vertically adjustable brackets 56, one of which is placed on each side of the machine as shown in Fig. 1, and each of the brackets are adjustably secured to the frame 34 of the machine by screws 57 which extend through slots 58 in the brackets 56, and are threaded into the frame 34, as shown in Figs. 1 and 4. The plate 14 is secured to the brackets 56 at each end by screws 59, one of which is shown in Fig. 4. The lower plate 14 is made adjustable by clamping it at points along the slots 58 by the screws 57 to take care of any variation in the diameter of the roll 11, and it is normally adjusted so that the top of the plate will be substantially level with the top surface of the bottom roll 11 and the top surface of the supporting rolls 19.

The upper cover edge folding plate 13 is adjustable to accommodate heels of different thicknesses, and it is carried by two vertically movable brackets 60, one of which is placed on each side of the machine. The brackets 60 are vertically adjusted on the frame 34 by thumb screws 61, which are threaded into the frame 34. The construction for holding one of the brackets 60 on the frame 34 is shown in Fig. 4. It comprises a screw 62 which passes through the slot 63 in the bracket 60 and is threaded into the frame 34. The securing screw 62 is adapted to clamp the bracket 60 to the frame 34, but when it is loosened the thumb screw 61 is adapted to move the plate 14 up and down by a swivel connection 64 between a shoulder 65 on the bracket 60 and a head 66 on the lower end of the thumb screw 61.

A brake 67 for the driven shaft 38 of the lower roll 14 is provided to prevent the cams 37 from overrunning when it is disengaged from the motor 28 by the one revolution clutch 29. The brake 67 comprises a band 68 having a lining 69 which operates upon a drum 70 secured to the shaft 38. The band is adjustable on the drum 70 by a bolt 71 which extends through ears 72 on the band 68.

Referring to Figs. 1 and 4, the one revolution clutch 29 is a conventional clutch in which the drive shaft 73 extending from the motor 28 to the clutch 29 runs continuously, and the clutch is provided with a cam 74, which disengages the shaft 73 from the shaft 38 when the end of the arm 75 of an L-shaped lever 76 engages the notch 77 in the surface of the cam 74, as shown particularly in Fig. 4. The arm 75 of the lever 76 is pressed towards the surface of the cam 74 by a spring 78, which is attached at one end to the lever 76, and at the other end to the frame 34 of the machine. The arm 79 of the lever 76 is pivoted on a pin 80 in a bracket 81 which is attached to the frame 34. The arm 79 is manually operated in opposition to the spring 78 by a cord 82, which is adapted to pull the upper end of the arm 75 out of the notch 74 when it is desired to have the clutch 29 engage the driven shaft 38 with the shaft 73 driven by the motor 28. The cord 82 is released immediately after the arm 75 is disengaged from the notch 77, and the spring 78 immediately pulls the end of the arm 75 against the surface of the cam 74. When the cam surface has made one complete revolution it is stopped by the engagement of the end of the arm 75 with the notch 77. The clutch 29 immediately disengages the shaft 38 from the driving shaft 73, and the shaft 38 and the cam 37 affixed thereto is immediately stopped by the braking action of the brake 67 in substantially the same position as shown in the drawings, having particular ref-

6

erence to Fig. 4. In that position a covered heel 18', as in Fig. 3, has just been discharged and the machine is ready to receive the assembly 18 of Fig. 2. The manually operated cord 82 extends to the front of the machine so that it may be conveniently operated by the operator with either his foot or hand depending upon the mechanism desired. As shown the cord 82 passes over a pulley 83 (Fig. 4) mounted on the frame 34 and extends to the front of the machine over a pulley 83 (Fig. 1) and downwardly to the pivoted pedal 85 to which the cord 82 is secured. The pedal 85 is pivoted on a bracket 86 attached to the frame 34 and may be arranged at a height suitable for operation by the hand or the foot of the operator.

In the operation of the heel covering machine, the operator applies the adhesively coated side 15 of the heel cover to the latex coated heel foundation 17 and inserts the assembled heel cover and heel foundation 18 between the vertical rollers 12 with the heel foundation 17 resting upon the supporting rollers 27. The assembly 18 is pushed forwardly between the rolls by the operator to the position shown in Figs. 4 and 5. The operator then puts the machine in motion by pressing the pedal 85 which causes the one revolution clutch 29 to connect the shaft 38 of the lower horizontal roll 11 with the motor 28. The cams 37 on each end of the shaft 38 are driven in the direction of the arrow A as shown in Fig. 4, and the raised portions 55 of the side cam surfaces 44 immediately pushes the rollers 51 to the side and forces the vertical rolls 12 toward each other and also inwardly towards the nip of the horizontal rolls 10 and 11. The heel assembly 18 is pushed between the nip of the rolls 10 and 11 and presses the adhesively coated folded over edges 22 of the heel cover to the latex coated heel foundation 17, as the assembly is drawn between the horizontal rolls 10 and 11. At the end of one complete revolution of the shaft 38, the roll 11 and the cam 37 attached thereto, the clutch 29 automatically disengages the shaft 38 from the motor driven shaft 73, and the machine is stopped in the position shown in the drawings for the reception of the next heel assembly 18 of Fig. 2. During the revolution, the covered heel 18', shown in Fig. 3 is discharged from the rear end of the machine.

While the preferred form of this invention has been shown and described herein somewhat in detail, it is to be understood that changes may be made without departing from the spirit of this invention, and it is intended to claim such changes which fall within the scope of the appended claims.

Having thus described my invention, what I claim and desire to protect by Letters Patent is:

1. A heel covering machine comprising a pair of horizontal rolls having resiliently yieldable surfaces, means for resiliently forcing one of said rolls towards the other for pressing the edges of the heel cover to the top and bottom surfaces of the heel foundation to be covered as it passes between said rolls, a pair of vertical rolls having resiliently yieldable surfaces positioned in front of said horizontal rolls and separated by a distance less than the width of the heel foundation for pressing the heel cover to the side edges of the foundation, means positioned between said pairs of horizontal and vertical rolls for folding the edges of said cover over the top and bottom surfaces of said heel foundation be-

fore such edges of said cover are passed between said horizontal rolls, and means for driving at least one of said horizontal rolls for drawing said heel and cover between said rolls.

2. A heel covering machine comprising a pair of horizontal rolls having yieldable peripheral surfaces, means for resiliently forcing one of said rolls towards the other for pressing the edges of the heel cover to the top and bottom surfaces of the heel foundation to be covered, means for driving at least one of said rolls to draw said heel foundation between said pair of rolls, means geared to said driven roll for intermittently forcing said rolls apart against the resistance of said resilient means to permit the entry of said heel between said rolls, a pair of vertical rolls having yieldable peripheral surfaces positioned in front of said horizontal rolls and adapted to press the heel cover to the side edges of said heel foundation.

3. A heel covering machine comprising a pair of horizontal rolls having yieldable peripheral surfaces for pressing the edges of the heel cover to the top and bottom surfaces of the heel foundation to be covered, a pair of vertical rolls positioned in front of said horizontal rolls and having yieldable, resilient, peripheral surfaces adapted to press the heel covering to the sides of the heel foundation, resilient means for forcing said horizontal rolls together, cam actuated means for separating said horizontal rolls to permit the width dimension of the heel to enter therebetween, a second cam actuated means for forcing said vertical rolls towards each other

5 and simultaneously towards said horizontal rolls to initially force the heel foundation therebetween, and means for driving at least one of said horizontal rolls and said first and second cam actuated means.

4. A heel covering machine comprising a pair of horizontal rolls having yieldable peripheral surfaces for pressing the edges of the heel cover to the top and bottom surfaces of the heel foundation to be covered, a pair of vertical rolls positioned in front of said horizontal rolls and having yieldable, resilient, peripheral surfaces adapted to press the heel covering to the sides of the heel, a support for the heel positioned between said vertical rolls, a pair of heel cover edge folding plates positioned between said horizontal and said vertical rolls, one of said plates being positioned substantially on the level of the supporting surface of said heel support, and the other of said plates being vertically adjustable and placed above the other plate, resilient means for forcing said horizontal rolls together, a cam for actuating one of said horizontal rolls to space it from the other the distance required to permit the heel to enter therebetween, a cam for actuating said vertical rolls towards each other and simultaneously towards said horizontal rolls to initially force the heel therebetween, and means for driving at least one of said horizontal rolls and both said cams.
